3 Claims. (Cl. 301—9)

My invention relates to improvements in quick detachable wheel hubs. The objects of the invention are to provide means for securing the component parts of the hub together which will hold them securely in fixed position against all strains incidental to driving and to enable them to be separated by simple manipulation of very few parts. A further object is to provide means whereby the wheel is supported on the hub prior to fastening, so that the registration of the hub parts may be obtained without having to support the weight of the wheel by muscular effort.

The invention consists essentially of a hub and a shell slidably mounted thereon and a concentrically disposed fastening means for securing said shell against endwise movement upon the hub, as will be more fully described in the following specification and shown in the accompanying drawing, in which:—

Fig. 1 is a longitudinal sectional view of the invention.

Fig. 2 is a transverse view showing the hub thread.

Fig. 3 is a transverse view showing the cap nut thread.

Fig. 4 is a projection of the thread showing the lead for the cap nut threads.

Fig. 5 is a fractionated longitudinal sectional view of a modification.

Fig. 6 is a longitudinal sectional view showing a modified locking means.

Fig. 7 is a fractionated plan view of same.

In the drawing like characters of reference indicate corresponding parts in each figure.

The numeral 1 indicates an axle to which is secured a hub 2. The hub 2 consists of a sleeve 3 provided at its inner end with a flange 4 which is provided with a plurality of studs 5 arranged equidistantly around the sleeve. The studs 5

are bevelled off at their free ends as at 6 and are provided with a sloping shoulder 7 at their connecting ends. The sleeve 3 is provided at its inner end with a tapered shoulder 8 and is provided at its outer end with a breech block thread

9 or a thread which is cut away at regular intervals of its circumference to define gaps 10.

Fitted upon the hub 2 is a wheel shell 11 which consists of a cylindrical portion 12 to which spokes 13 are secured in any desired manner.

A flange 14 extends inwardly from the portion 12, and the inner periphery of the flange is connected with a sleeve 15 which fits snugly yet freely upon the sleeve 3 of the hub 2. The outer end of the sleeve 15 is outwardly splayed as at 16, and the intersection of said sleeve with the

shell flange 14 is splayed to fit the tapered shoulder 8 of the hub 2. The flange 14 is provided with apertures 17 through which the studs 5 pass, but the margins of said apertures come to rest adjacent the base of the sloping shoulder 7 of the said studs so as to provide a positive and accurate ultimate engagement of the flange 14 while allowing the apertures 17 to be easily brought into register with said studs.

The breech block thread 9 is engaged by a cap nut 18 having a corresponding thread 19 divided by corresponding gaps 20, so that in fitting the cap nut the threads of the nut are passed longitudinally along the sleeve through the gaps 10 until it is bottomed, and then turned to right or left according to the thread being right or left hand as the case may be. In order that the meeting ends of the segments of the threads 9 and 19 do not abut to prevent free turning movement, as would be the case were the ends cut off at substantially a right angle to the line of the threads, the entering ends of the male or sleeve threads 9 are sloped off as at 21, so that on initial turning movement being given to the cap nut its threads ride up the sloped ends of the corresponding threads and allow the threads to engage with ease.

The inner peripheral edge of the cap nut 18 is tapered as at 22 to conform to the splay 16 of the sleeve 15, so that when the cap nut is screwed up securely the ends of the sleeve are concentrically aligned between the tapered shoulder 8 of the hub 2 and the taper 22 of the cap nut 18. The cap nut 18 is provided at its free end with a stud 23 which is engaged by a nut 24 preferably rotatably mounted in a cover plate 25. The cover plate 25 is provided with a bevelled flange 26 which abuts a corresponding flange 27 upon the free end of the cylindrical portion 12 of the wheel shell 11. This cover plate is provided with inwardly projecting lugs 28 which are adapted to engage flats 29 of the cap nut 18 in a similar manner to the jaws of a wrench.

In the modification shown in Figure 5 instead of providing a plurality of convolutions of thread on the hub sleeve and cap nut, two segments of convolutions only are provided on each of the parts, the male thread being at the outer end of the sleeve as at 30 and the female thread of the nut cap being at the inner end as indicated in dotted line as at 31.

In the modified locking means shown in Figures 6 and 7, the cap nut 18 is provided with arcuate slots 32 which register with the gaps 20, through

which slots, legs 33 of a U-shaped member 34 project to fill said gaps and the gap 10 of the hub sleeve. When the cap nut is screwed into place the U-shaped member is inserted and is held in position by a nut 35 upon the stud 23 which passes through said U-shaped member. It may be preferred to taper one or both sides of the legs 33 as at 36 in order to assist in driving the threads of the hub sleeve and cap into tighter engagement.

When fitting a wheel, the shell 11 is slipped onto the sleeve 3 of the hub 2 and is rocked thereabouts until the studs 5 register with the apertures 17 when it is thrust substantially into contact with the flange 4. The cap nut 18 is then applied to the thread 9 and tightened up with a suitable wrench, finally the cover plate 25 is then placed in position and the nut 24 screwed up upon the stud 23. When this is done, the frictional contact between the coacting surfaces of the cover plate flange 26 and the outer flange 27 of the shell 11 and the grip of the nut 24 on the stud 23 is sufficient to definitely lock the cap nut against removal through road shock, starting torque or any other strain that the wheel might be subjected to.

In the modified form shown in Figures 6 and 7, the legs 33 of the U-shaped member 34 are projected into the gaps 10 and 20 and are held in adjusted position by the nut, thus locking the nut cap against removal.

What I claim as my invention is:

1. A quick detachable wheel comprising a hub sleeve having at its outer end a breech block thread, a wheel shell having a sleeve adapted to

slidably engage the hub sleeve, means for preventing rotation of the shell sleeve upon the hub sleeve, a cap nut adapted to engage the breech block thread and bind against said shell sleeve, and means threadedly engaging the cap nut for frictionally engaging the periphery of the shell and for locking the cap nut against rotation.

2. A quick detachable wheel comprising a hub sleeve having at its outer end a breech block thread, a wheel shell having a sleeve adapted to slidably engage the hub sleeve, means for preventing rotation of the shell sleeve upon the hub sleeve, a cap nut adapted to engage the breech block thread and bind against said shell sleeve, and means for locking the cap nut to the hub sleeve, said locking means consisting of a bevelled flanged member extending across the shell and contacting therewith, and screw means concentric with the member for joining said member to the cap nut.

3. A quick detachable wheel comprising a hub sleeve having at its outer end a breech block thread, a wheel shell having a sleeve adapted to slidably engage the hub sleeve, means for preventing rotation of the shell sleeve upon the hub sleeve, a cap nut adapted to engage the breech block thread and bind against said shell sleeve, and means for locking the cap nut to the hub sleeve, said locking means consisting of a plate having a bevelled peripheral flange adapted to bear upon a complementary peripheral surface of the shell, and a concentrically mounted screw for fastening the plate to the cap nut.
